United States Patent Office

Des. 180,269
Patented May 14, 1957

180,269

TILE DISPLAY STAND OR SIMILAR ARTICLE

Robert M. Brittingham, Dallas, Tex.

Application May 10, 1954, Serial No. 30,407

Term of patent 14 years

(Cl. D80—9)

Fig. 1

Fig. 2

Fig. 3

Figure 1 is a top plan view of a tile display stand, showing my new design;

Figure 2 is a side elevational view, and

Figure 3 is a fragmentary perspective view of the upper portion thereof.

I claim:

The ornamental design for a tile display stand or similar article, substantially as shown.

References Cited in the file of this patent

UNITED STATES PATENTS

719,164	Walk	Jan. 27, 1903
770,756	Hynek	Sept. 27, 1904
1,382,092	Kilmer	June 21, 1921
2,442,709	Ramsdell	June 1, 1948

FOREIGN PATENTS

495,000	Belgium	Oct. 1, 1950